CLAIM

The ornamental design for a smart luggage zipper lock, as shown and described.

DESCRIPTION

FIG. 1 is a perspective view of a smart luggage zipper lock, showing our new design,

FIG. 2 is a top plan view thereof;

FIG. 3 is a bottom plan view thereof;

FIG. 4 is a side elevation view thereof;

FIG. 5 is an opposite side elevation view thereof;

FIG. 6 is a front elevation view thereof; and,

FIG. 7 is a rear elevation view thereof.

The broken lines shown in the drawings illustrate unclaimed portions and form no part of the claimed design.
